UNITED STATES PATENT OFFICE.

SYLVANUS F. BOWSER, OF FORT WAYNE, INDIANA, ASSIGNOR TO S. F. BOWSER & COMPANY, INCORPORATED, OF FORT WAYNE, INDIANA, A CORPORATION OF INDIANA.

SOLDERING-MACHINE.

1,123,082.

Specification of Letters Patent. Patented Dec. 29, 1914.

Application filed January 12, 1911. Serial No. 602,226.

To all whom it may concern:

Be it known that I, SYLVANUS F. BOWSER, a citizen of the United States, residing at Fort Wayne, in the county of Allen and State of Indiana, have invented certain new and useful Improvements in Soldering-Machines, of which the following is a specification.

This invention relates to improvements in soldering machines and more particularly to machines adapted for soldering the ends of tanks or receptacles, which are of angular construction in cross section, and the primary object of the present invention is to provide an improved machine of this character which will be simple, durable and cheap in construction and effective and efficient in operation.

A further object is to provide improved means for heating the article and improved means for imparting relative movement to the burner or heater and the article whereby one may be moved out of the way of the other to permit the article to be readily adjusted or removed.

A further object is to provide improved means whereby such relative movement will automatically control the supply of fuel to the burner or heater.

30 A further object is to provide improved means for cooling the article.

To the attainment of these ends and the accomplishment of other new and useful objects, as will appear, the invention consists substantially in the features of novelty hereinafter more fully described and claimed and shown in the accompanying drawings exemplifying the invention, and in which—

40 Figure 1 is a top plan view of an improved machine of this character constructed in accordance with the principles of this invention. Fig. 2 is a detail front elevation of the right-hand end of the machine shown in Fig. 1. Fig. 3 is an end elevation showing a tank in position in the machine.

Referring more particularly to the drawings the tank 10 is supported upon an adjustable carriage or support, which latter 50 comprises a platform 11 supported at one end of a frame work, which latter comprises uprights 12, 13. These uprights are spaced from each other and are connected for movement in unison, preferably by means of a connecting member 14. The platform

11 is inclined as shown and braces 15 are provided for maintaining the platform in this position. Spaced from the platform 11 and mounted upon the uprights is a second support designated generally by the reference numeral 16, which is provided with an inclined face 17 against which the side of the tank 10 is adapted to rest when its bottom engages and rests upon the platform 11. The face 17 of the support 16 is arranged at a substantially right angle to the support 11 so that when the tank is placed upon these supports and in the position shown in Fig. 3, one of the edges thereof will project into the space between the supports 11 and 16. The supporting frame work thus formed is adapted to be moved upon tracks or ways 18 and in order to permit of an easy adjustment thereof rollers 19 are provided at one end of the frame work. The frame work is provided at its forward end with means for advancing and retracting the same which comprises gear wheels 20, one of which is arranged adjacent each side or end of the machine and these gear wheels are connected by means of an axle 21 extending substantially the entire length of the machine. Supported by the frame work, preferably by means of the support 16, are racks 22, one of which is arranged above each of the gears 20 and with which the respective gears mesh. Similar racks 23 are secured to the tracks or ways 14 beneath each of the gears 20 and with which the respective gears mesh. An operating handle 24 is provided which is preferably connected to one end of the axle 21. With this construction it will be manifest that when the handle 24 is raised or lowered, the gear 20 through the medium of the racks 22, 23, will cause the tank supporting frame work to be moved forwardly or backwardly on the tracks or ways 14 according to the direction of movement of the handle 24. In order to limit the movement of the supporting frame in one direction, stops 25 may be provided which are secured to the frame and are adapted to engage the respective racks 23 when the supporting frame has reached the limit of its movement in the one direction. The edge of the tank which projects into the space between the supporting bases 11 and 17 is adapted to be heated by means of a plurality of burners 26, any

115

number of which may be provided and which extend the entire length of the machine. These burners 26 have communication with a supply chamber 27 supported by 5 means of suitable supports 28^a and in such a position that when the tank supporting frame is at the limit of its forward movement, the burners 26 will be in position to direct a flame against the outer lower edge 10 of the tank 10 for the purpose of soldering. After the solder has been placed in the tank the latter may be rolled upon the support in order that the entire joint may be heated.

Fuel may be supplied to the chamber 27 15 from any suitable source of supply and by means of a pipe or conduit 28 within which is arranged a quick-acting controlling valve 29. This valve 29 is adapted to be automatically actuated by the adjustment of the 20 tank supporting frame and in order that the valve may be opened when the frame has reached the proper position to direct the flame thereagainst and to be closed by the adjustment of the frame in the opposite direction 25 when the tank is moved away from the burner, an operating link or lever 30 is provided, which is supported independently of the tank supporting frame. A portion of this operating link or lever passes 30 through guides 31 on the tank supporting frame, preferably the platform 11 so as to move freely therethrough and these guides 31 are so arranged with respect to the valve 29 that when the tank supporting frame is 35 adjusted, the movement of this link or lever 30 through the guides 31 will automatically open or close the valve 29 according to the direction of movement of the tank supporting frame. A pilot tube 32 for lighting 40 the burners 26 leads from the pipe 28, and an additional valve 33 may be provided in the pipe 28 whereby all supply of fuel may be shut off from the chamber 27.

The burners 26 and the supply chamber 45 27 are stationary with respect to the movement of the tank supporting frame and in operation the tank supporting frame is adjusted in a direction to move the supporting face or platform 11 away from the 50 burner so that the tank 10 may be placed in the frame with its bottom resting against the support 11 and with its side resting against the face 17. This adjustment of the frame will close the valve 29. When 55 the tank is properly positioned the lever or handle 24 is operated so as to move the supporting platform 11 toward the burner 26 and this movement will automatically open the valve 29 so that fuel may be supplied 60 to the burners. The flame from the burners being directed against the article will heat the joint to be soldered so that the soldering material will flow thereinto. After the soldering has been completed, the handle 24 65 is operated in the opposite direction to move

the tank away from the burner and to shut off the supply of fuel to the burner. In order to cool the joint thus soldered, a cooling fluid may be employed and directed through the nozzles or burners 26. This 70 cooling fluid is adapted to be supplied from any suitable source of supply through a pipe 34 which latter has communication with the chamber 27 so that cooling fluid may be discharged through the burners or 75 nozzles 26 against the tank when the flame is extinguished, and a controlling valve 35 is provided in the pipe 34 for controlling the supply of cooling fluid to the nozzles. When it is desired to use this cooling fluid 80 for cooling purposes the supply of fuel to the burners may be shut off by operating the valve 33 without adjusting the tank supporting frame, after which the valve 35 may be opened. An additional cooling 85 means is provided for cooling the joint by a cooling fluid directed against the joint from under the tank and for this purpose a sprayer 36 in the form of a pipe is arranged in convenient position. This sprayer 90 36 extends substantially the entire length of the frame and receives its supply of cooling fluid, preferably water, from a pipe 37 which latter receives its supply from any suitable source. A quick acting valve 38 is 95 arranged in the pipe 37 and an operating handle or lever 39 for controlling this valve 38 is provided and is arranged in a convenient position for the operator. The sprayer 36 is preferably spaced some distance from the nozzles or burners 26 and is 100 preferably arranged to direct the fluid therefrom against the tank in a direction opposed to the direction in which the flame is directed against the tank. After the soldering 105 operation has been completed and the tank supporting frame adjusted to move the tank away from the burner and to shut off the supply of fuel, the valve 38 is opened to permit the discharge of the cooling fluid. 110 A drip or catch pan 39^a is provided for catching the water discharged from the spraying nozzle 36. This spraying nozzle 36 may be supported in any desired or convenient manner, preferably from the support 11 by means of brackets 40.

What is claimed as new is—

1. In a machine of the class described, the combination of separate spaced supports for an article to be soldered arranged at an angle to each other with both of which an article has engagement and spaced to permit an article placed thereon to project between them, a burner disposed to direct its flame against an article between the supports, said burner and supports being relatively movable, means for imparting such relative movement, means for supplying fuel to the burner, controlling means for said supply, and means for supplying 125

another fluid through the burner to cool an article soldered.

2. In a machine of the class described, the combination of spaced supports for an article arranged at an angle to each other with both of which an article has engagement, a burner disposed to direct its flame against that portion of an article between the supports, said burner and said supports being relatively movable, means for imparting such relative movement, fuel supply means for the burner, means for supplying another fluid through the burner to cool the article, and means individual to both the supply means for controlling the passage of fluid through them.

3. In a machine of the class described, the combination of spaced supports for an article with surfaces fixed with relation to each other arranged at an angle to each other and spaced to permit an article placed thereon to project between them, a burner arranged to direct its flame against an article placed between the supports, means for supplying fuel to the burner, means for controlling the supply of fuel, and means for directing another fluid through the burner against an article between the supports for cooling the article when the flame is extinguished.

4. In a machine of the class described, the combination of spaced supports for an article with supporting surfaces at angles fixed with relation to each other, a burner arranged to direct its flame against one face of an article placed between the supports, means for supplying the burner with fuel, means for controlling said supply, and means for supplying the burner with another fluid to be directed against the face of an article between the supports to cool the article.

5. In a machine of the class described, the combination of spaced supports for an article fixed with relation to each other, a burner arranged to direct its flame against one face of an article placed between the supports, means for supplying the burner with fuel, means for controlling such supply, and means whereby another fluid may be supplied to and directed from the burner against the same face of an article when the flame is extinguished.

6. In a machine of the character described, the combination of a support for the article, a burner with relation to which the support is movable to bodily move the article toward and away from the burner, means comprising a rack and gear for imparting such movement to the support, and means for limiting the movement of the support in one direction.

7. In a machine of the character described, the combination of a support for the article, a burner with relation to which

the support is movable to bodily move the article toward and away from the burner, means comprising a rack and gear for imparting such movement to the support, means coöperating with the gear for limiting the movement of the support in one direction, and means whereby the movement of the support will automatically control the supply of fuel to the burner.

8. In a machine of the character described, the combination of a support for the article, a way upon which the support moves, racks supported by the way and the support, a gear disposed between and engaging the racks, means for operating the gear to advance or retract the support, and a burner with respect to which the support is movable.

9. In a machine of the character described, the combination of a support for the article, a way upon which the support moves, racks supported by the way and the support, a gear disposed between and engaging the racks, means for operating the gear to advance or retract the support, a burner with respect to which the support is movable, and means whereby such movement of the support will automatically control the supply of fuel to the burner.

10. In a machine of the class described, the combination of spaced supports fixed with relation to each other spaced to permit an article placed thereon to project between them, a way upon which the supports are movable, racks on the way and the support, a gear disposed between and engaging the racks to advance and retract the supports, a burner arranged to direct a flame against an article placed between the supports and with relation to which burner the supports are movable for moving an article toward or from the burner, and means whereby the supply of fuel to the burner is controlled by the movement of the supports.

11. In a machine of the class described, the combination of spaced supports fixed with relation to each other and spaced to permit an article placed thereon to project between them, a way upon which the supports are movable, racks on the way and the support, a gear disposed between and engaging the racks to advance and retract the supports, a burner arranged to direct a flame against an article placed between the supports and with relation to which burner the supports are movable for moving an article toward or from the burner, means whereby the supply of fuel to the burner is controlled by the movement of the supports, and means for directing a cooling fluid through the burner against that portion of an article placed between the spaced supports.

12. In a machine of the class described, the combination of a support for an article

to be soldered, a series of burners arranged adjacent the edge of the support, said burner and support being relatively movable toward and from each other, and means for imparting such relative movement, said article moving with the support, and said burners extending from side to side of the machine in the path of such movement.

13. In a machine of the class described, 10 the combination of movable spaced supports for an article to be soldered, a burner having a series of jet openings arranged to direct its flame against one face of an article placed between the supports, means for 15 supplying the burner with fuel, and means for controlling such supply, the supports carrying bodily an article to be soldered and said jet openings extending from side to side of the machine and arranged in the 20 path of movement of the supports.

14. In a machine of the class described, the combination of spaced supports for an article to be soldered, a burner having a series of jet openings arranged to direct its 25 flame against one face of an article placed between the supports, means for supplying the burner with fuel, means for controlling such supply, the supports permitting an article to be soldered to be rolled thereon

and said jet openings being arranged in the 30 line of rolling movement of an article, and means whereby another fluid may be directed through the burner against the same face of an article soldered when the flame is extinguished.

15. In a machine of the class described, the combination of spaced supports for an article to be soldered, a burner having a series of jet openings arranged to direct its flame against one face of an article placed 40 between the supports, means for supplying the burner with fuel, means for controlling such supply, the supports being adapted to allow an article to be soldered to be rolled thereon and said jet openings being arranged in the line of rolling movement upon the support, and means whereby another fluid may be supplied through the jet openings to be directed against the soldered face 45 of an article when the flame is extinguished.

In testimony whereof I have signed my name to this specification, in the presence of two subscribing witnesses, on this ninth day of January, A. D. 1911.

SYLVANUS F. BOWSER.
